(57) **CLAIM**

The ornamental design for test strips for medical or laboratory purposes, as shown and described.

DESCRIPTION

1. Test strip for medical or laboratory purposes

2. Test strip for medical or laboratory purposes

1.1 : Front

1.2 : Back

1.3 : Left

1.4 : Right

1.5 : Top

1.6 : Bottom

1.7 : Perspective

1.8 : Cross sectional

2.1 : Front

2.2 : Back

2.3 : Left

2.4 : Right

2.5 : Top

2.6 : Bottom

2.7 : Perspective

2.8 : Cross sectional

FIG. 1.8 is a cross-sectional view taken along line 8-8 of FIG. 1.7; FIG. 2.8 is a cross-sectional view taken along line

(Continued)

16-16 of FIG. 2.7; the broken lines illustrate portions of the test strips for medical or laboratory purposes which form no part of the claimed designs.

1 Claim, 16 Drawing Sheets

(58) Field of Classification Search

CPC . G01N 21/6428; G01N 33/49; G01N 33/6854
